T. J. MOORE,

DOOR SPRING.

APPLICATION FILED JAN. 24, 1919.

1,399,642.

Patented Dec. 6, 1921.

T. J. Moore, Inventor

By W. Murphy Jr., attorney

UNITED STATES PATENT OFFICE.

THOMAS J. MOORE, OF WASHINGTON, DISTRICT OF COLUMBIA.

DOOR-SPRING.

1,399,642.

Specification of Letters Patent.

Patented Dec. 6, 1921.

Application filed January 24, 1919. Serial No. 272,835.

To all whom it may concern:

Be it known that I, THOMAS J. MOORE, a citizen of the United States, residing at Washington, in the District of Columbia, have invented certain new and useful Improvements in Door-Springs; and I do hereby declare the following to be a full, clear, and exact description of the invention, such as will enable others skilled in the art to which it appertains to make and use the same:

This invention relates to door springs and the primary object of the invention is to provide an improved means for tensioning the spring, so that the strength thereof can be readily regulated.

Another object of the invention is to provide an improved door spring of the coil type having the upper bracket thereof carrying a pivoted pawl or latch which is mounted upon one of the attaching screws, the pawl or latch being adapted to engage one of the teeth formed on the upper end of the coil spring securing device so that the coil spring can be turned to the required tension and the pawl or latch can be swung into engagement with the teeth and thus hold the spring against movement.

A further object of the invention is to provide an improved door spring of the above character, which is durable and efficient in use, one that is simple and cheap to manufacture, and one that can be placed upon the market at a reasonable cost.

With these and other objects in view, the invention consists in the novel construction, arrangement and formation of parts, as will be hereinafter more specifically described, claimed and illustrated in the accompanying drawings, forming a part thereof, in which:

Figure 1 is a front elevation of the improved door spring applied to a door.

Fig. 2 is an enlarged front elevation of the upper end of the spring, and bracket, showing the spring being tensioned.

Fig. 3 is a front elevation of the upper bracket removed from the coil spring.

Fig. 4 is a side elevation of the upper bracket.

Referring to the drawings in detail, wherein similar reference characters designate corresponding parts throughout the several views, the numeral 1 generally indicates the improved door spring, which is

adapted to be applied to the door 2 and casing 3 in the ordinary manner.

The improved door spring includes a coil spring 4 of the usual, or any preferred form, generally used for this class of door springs having its upper and lower terminals secured to stems 5 and 6 of the upper and lower brackets 7 and 8, respectively. The brackets 7 and 8 have the stems 5 and 6 thereof recessed as at 9, for receiving the ends of the coil spring, which are bent into the same.

The lower bracket, which is of the ordinary construction, includes the attaching plate 10 through which the attaching screws 11 extend and an outwardly extending angular arm 12 which supports the stem 6.

The upper stem 5 is made independently of the bracket 7 and has a shoulder 13 formed intermediate the ends thereof, upon which the collar 14 of the upper bracket 7 rests. The annular shoulder 13 is provided with diametrically extending recesses 15 for a purpose, which will hereinafter more fully appear. The upper end of the stem 5 is provided with inwardly extending slots 16, which define radially extending teeth 17. The slots 16 terminate short of the annular shoulder 13 and this forms a bearing surface for engaging the collar 14. The collar 14 extends at right angles to the attaching plate 18 of the upper bracket and this collar is formed adjacent to the lower end thereof and is provided with an upwardly extending inclined reinforcing cleat 19 which holds the collar against distortion. The attaching plate 18 is provided with outwardly extending ears 20 through which the attaching screws 21 extend. A pawl or latch member 22 has its rear end 23, thereof provided with an aperture 24, through which protrudes one of the attaching screws 21. This forms a convenient means for pivotally securing the pawl or latch member in proper position for engaging in one of the grooves 16, so as to hold the spring in proper tensioned position. The pawl is located directly opposite to the strengthening rib 19.

In operating the improved device, a suitable pin is inserted in one of the openings 15 near the annular shoulder 13, as clearly shown in Fig. 2 of the drawings, and the latch member 22 is thrown back on the screw 21 and the collar, carrying the stem 110

5 therewith, is turned until the spring reaches the required tension, when the pawl or latch is then thrown downward into engagement with the teeth which prevents 5 further movement of the spring in relation to the upper bracket 7. From the foregoing description it can be seen that an improved door spring is provided of exceedingly simple and durable construction, 10 in which the spring can be readily tensioned in a convenient and expeditious manner.

In practice, I have found that the form 15 of my invention illustrated in the accompanying drawings and referred to in the above description, as the preferred embodiment, is the most efficient and practical; yet realizing the conditions concurrent with the adoption of my device will necessarily vary, 20 I desire to emphasize that various minor changes in details of construction, proportion and arrangement of parts may be resorted to, when required without sacrificing any of the advantages of my invention as 25 set forth.

What I claim as new is:

1. A door spring device including a spring, a collar provided with an opening,

a latch to extend over said opening, a stem secured to said spring, means on the stem 30 to underlap the collar, said stem having a portion extending rotatably and slidably through the opening and provided with means to engage the latch through upward movement of the portion, and means to 35 facilitate the depression of the stem to release it from the latch and collar.

2. A door spring device including a spring, a bracket having a collar provided with an exposed opening, an exposed latch 40 on said bracket movable to and from a position over said opening, a stem secured to said spring, a shoulder on the stem to underlap the collar, said stem having a portion extending rotatably and slidably 45 through the opening and provided with a groove to receive the latch when over said opening through upward movement of the portion, and means coöperating with the shoulder operable to depress the stem to 50 release it from the latch and collar.

In testimony whereof I affix my signature in presence of a witness.

THOMAS J. MOORE.

Witness:

BURNETT S. JONES.
